			249/61

Primary Examiner — Richard E Chilcot

(57)

CLAIM

The ornamental design for an ice cube device, as shown and described.

DESCRIPTION

1. Ice cube device
- 1.1 : Perspective
- 1.2 : Front
- 1.3 : Back
- 1.4 : Left
- 1.5 : Right
- 1.6 : Top
- 1.7 : Bottom

The reproductions show the design of a new ice cube device; the reproductions are rendered images in grey tones, as protection is not claimed for color.

1 Claim, 7 Drawing Sheets
